UNITED STATES PATENT OFFICE.

WILLIAM C. OVENDEN, OF WEST BOYLSTON, MASSACHUSETTS.

FOOT-REST.

No. 926,207.

Specification of Letters Patent. Patented June 29, 1909.

Application filed May 9, 1908. Serial No. 431,959.

to all whom it may concern:

Be it known that I, WILLIAM C. OVENDEN, a citizen of the United States, residing at West Boylston, in the county of Worcester and State of Massachusetts, have invented a new and useful Foot-Rest, of which the following is a specification.

This invention relates to a foot-rest to be applied to heat radiators, especially steam radiators.

Several forms of foot-rests and folding shelves have been invented some of which have been adapted to steam radiators.

This invention is designed as an improvement over the same for the purpose of obviating certain disadvantages which they usually possess. As a general thing, those which are so constructed that they can be folded out of the way when not in use are provided with devices which stick out from the radiator when so folded in such a way as to catch the clothing and present an unsightly appearance.

This invention is designed to provide a simple and inexpensive construction which can be folded up out of the way without providing any projections of this kind and without having any features which are unsightly when the device is so folded, and in which the stops for limiting the position of the foot rest and holding it in horizontal position will be integral with the rest and supporting brackets, thus facilitating the manufacture of the device.

Further objects and advantages of the invention will appear hereinafter.

Reference is to be had to the accompanying drawings in which,

Figure 1 is a plan of a steam radiator showing a preferred form of the invention applied thereto, and Figs. 2 and 3 are sectional views of the same showing the foot-rest respectively in operative and folded positions.

In the form shown in the drawings, the device involves a pair of supports 10 each in the form of a rod adapted to extend through the radiator between the sections thereof and having a fixed head 11 on the end thereof for bearing against the rear of the sections. The other end of the rod is threaded and is provided with a nut adapted to screw up against a bracket 12 to force the same against the front of two radiator sections so as to hold the support properly in position. This bracket is provided with one or more forwardly extending ears 13 on which the

foot-rest proper 14 is pivoted by means of a pin 15. The bracket is also provided with a bottom flat surface 16 and the foot-rest with a projection 17 adapted to engage said flat surface when the foot-rest is swung out into horizontal position. This projection 17 extends upwardly from the foot-rest on a gentle curve and the surface 16 is located above the bottom of the pivot 15.

It will be observed that the ears 13 extend forwardly and downwardly from the main part of the bracket, and that at their lower ends they have extensions 18 located along the fronts of the radiator sections. It will also be observed that the foot-rest is provided with an upward projection 19 located between the ears 13 for receiving the pin 15. This projection extends above the top of the arm 17 when the foot-rest is in horizontal position. Now when the foot-rest is not in use it is folded up against the front of the radiator on an incline, as indicated in Fig. 3. In this position the projection 17 does not extend out into the room where it is likely to interfere with the clothing of passersby and at the same time the center of gravity of the foot-rest is behind the pivot 15 because the latter is located at some distance from the front of the radiator. On account of the relative location of the pivot and projection 17 the device can be made in a very simple manner of cast metal if desired and the parts can be held in horizontal position, and also in inclined folded up position, without projecting far out into the room. The invention is shown in a form in which two of these brackets and accompanying parts are provided and that will generally be the construction of the device but it will be understood that any number of these parts may be employed according to convenience.

While I have illustrated and described a preferred embodiment of the invention, I am aware that modifications may be made there- by any person skilled in the art without departing from the scope of the invention as expressed in the claim. Therefore, I do not wish to be limited to all the details shown, but

What I do claim is:—

The combination with a pair of supporting brackets, each adapted to be attached to two sections of a radiator and each having a bottom bearing surface at the front thereof, of a pivot supported by each bracket at a distance in front of said surface and below it,

2
and a foot-rest, capable of swinging upwardly thereon concentrically into an inclined position, and capable of resting in inclined position against the fronts of the radiator section against the fronts of the radiator section
5 tions, and having two integral upwardly extending projections near the rear end thereof for receiving said pivots and two integral rearward arms projecting above the centers of the pivots curved upwardly from the bottom
10 tom of the foot-rest to engage said bottom bearing surfaces when the foot rest is in horizontal position, whereby the foot rest is sup-

ported in horizontal position below the pivots and whereby said rearward projections extend out of the way when the foot rest is in 15 a vertical position.

In testimony whereof I have hereunto set my hand, in the presence of two subscribing witnesses.

WILLIAM C. OVENDEN.
